AUGER ICE MAKING MACHINE
Anthony J. Ross, 528 74th St.,
Holmes Beach, Fla. 33510
Filed May 24, 1966, Ser. No. 552,458
18 Claims. (Cl. 62—354)

This application is a continuation-in-part of the co-pending application of Anthony J. Ross, Ser. No. 510,298, filed Nov. 29, 1965, and now abandoned.

This invention relates to ice making apparatus for producing a flake ice product.

The present invention relates to improvements in ice making apparatus of the type disclosed in my prior Patent 3,101,598 and having a refrigerated cylindrical freezing wall for freezing water in a layer thereon and a helical ice remover for removing ice from the freezing wall. Such ice making apparatus operates to freeze ice in a layer on the freezing wall until the ice layer becomes sufficiently thick to be engaged by the rotating ice remover, and the ice remover then operates to strip the ice from the freezing wall. However, in the prior ice making apparatus, the ice remover sometimes tended to remove the ice from a major portion or even the entire freezing wall at one time, thereby producing peak loads on the ice remover drive mechanism which were higher than the torque required when the ice layer is removed in smaller sections. Further, when the ice remover is in the form of an axially expandable helical coil, considerably greater elongation of the coil occurs when the coil engages and removes a major portion or all of the ice from the evaporator at one time.

An object of this invention is to provide an ice making apparatus of the type having a helical ice remover for removing the ice from the freezing wall, and which is so arranged as to reduce peak loads on the ice remover drive mechanism.

Another object of this invention is to provide an ice making apparatus of the type having an ice remover in the form of an axially expandable helical coil for removing ice from the freezing wall, and which reduces the change in the axial dimensions of the coil during removal of the ice from the freezing wall.

Another object of this invention is to provide an ice making apparatus having a helical ice removing device for removing ice from a freezing wall and which enables production of relatively thick ice flakes.

Still another object of this invention is to provide an ice making apparatus having a rotary ice remover for removing ice from the outside of the cylindrical freezing wall and which ice remover has an improved arrangement for centering the same with respect to the freezing wall and for maintaining portions of the ice remover spaced from the freezing wall to produce ice flakes of preselected thickness.

Yet another object of this invention is to provide an ice making apparatus having a rotary ice remover for removing ice from the freezing wall, in which the ice remover has a helical ice engaging surface so arranged as to generate an undulated surface of revolution as it rotates relative to the freezing wall.

These, together with other objects and advantages of this invention will be better understood by reference to the following detailed description when taken in connection with the accompanying drawings wherein:

FIGURE 1 is a sectional view through the head of an ice making apparatus embodying the present invention, with the refrigerating apparatus and liquid level controls shown diagrammatically;

FIG. 2 is a transverse sectional view taken on the plane 2—2 of FIG. 1;

FIG. 3 is a fragmentary longitudinal sectional view

2

through the head of an ice making apparatus taken on the plane 3—3 of FIG. 1;

FIG. 4 is a sectional view taken on the plane 4—4 of FIG. 5 through the head of an ice making apparatus 5 having a modified form of ice remover;

FIG. 5 is a transverse sectional view taken on the plane 5—5 of FIG. 4;

FIG. 6 is a sectional view taken on the plane 6—6 of FIG. 7 through the head of an ice making apparatus 10 having still another form of ice remover;

FIG. 7 is a transverse sectional view taken on the plane 7—7 of FIG. 6;

FIG. 8 is a side elevational view of the ice remover of FIG. 6; and

FIG. 9 is a sectional view through the ice remover taken on the plane 9—9 of FIG. 8.

The ice making apparatus in general includes a freezing wall having means for refrigerating the same sufficient to freeze a layer of water thereon, a means for supplying water to the freezing wall, a rotary ice remover having an ice engaging surface mounted for rotation relative to the freezing wall to remove ice therefrom, and a drive mechanism for rotatably driving the ice remover. In accordance with the present invention, the ice engaging surface of the ice remover is preferably made helical with a noncircular configuration, as viewed in a direction axially of the rotatable ice remover, so that different portions of the ice engaging surface are spaced relatively different distances from the freezing wall and generate a non-cylindrical or undulated surface of revolution as it rotates relative to the freezing wall.

Reference is now made more specifically to the embodiment of the invention shown in FIGS. 1—3 of the accompanying drawings. The ice making apparatus preferably employs an internal evaporator including a tubular shell 10 defining a cylindrical freezing wall 11 on the outer surface thereof. The shell is herein shown closed at one end by a thickened wall 12 and at the other end by a plug 13 which advantageously extends inwardly from one end of the tubular wall 10 and defines a sealing face 13a spaced inwardly from the end of the freezing wall. Any suitable means may be provided for controlling the flow of refrigerant to and through the evaporator to cool the freezing wall thereof and, as diagrammatically shown herein, a refrigerating apparatus including a compressor 14, condenser 15 and refrigerant expansion control 16 connected to refrigerant supply and return lines 17 and 18 respectively, and which supply return lines extend into the evaporator. The refrigerant supply line 17 is conveniently formed with a reverse bend 17a at its inner end to direct the incoming refrigerant downwardly toward the bottom of the evaporator compartment, to thereby agitate the liquid therein and prevent the accumulation of oil and the like in the bottom of the evaporator. The return line 18 preferably extends to a point adjacent the upper end of the evaporator and has its return inlet 18a disposed adjacent the upper end of the compartment to return the gaseous or expanded refrigerant to the compressor.

The water to be frozen is preferably supplied to the freezing wall by immersing the same in the water and, for this purpose, there is provided an outer liquid jacket or vessel 25. Conveniently, the evaporator is formed with an enlarged head 26 at one end, which head extends outwardly and defines an annular wall 27 spaced outwardly from the freezing wall 11 and a radial shoulder or stop 28. The liquid vessel 25 is conveniently in the form of a sleeve 29 which surrounds the annular wall 27 and is sealed thereto as by an O-ring gasket 31. The water jacket is detachably mounted on the base 26 of the evaporator to facilitate cleaning of the apparatus and, as shown, is formed with an outwardly extending flange 32

hich is axially supported by engagement with the shoulder 28 on the base, and the water jacket is detachably secured in position on the base as by headed rivets 33 which extend through bayonet slots 34 in the flange 32. The vessel 25 defines a water reservoir around the evaporator and water is supplied to this reservoir through water inlet line 38, under the control of a float valve 39 or the like connected to a water supply line 41. The float valve maintains a preselected upper liquid level L in the vessel 25.

The rotary ice removing device 43 for removing ice from the freezing wall has a helical ice engaging surface 3a. The ice remover is preferably in the form of a coil which has only one end supported against axial movement so as to allow elongation and contraction of the coil under the stresses involved during ice removal. As shown, the coil 43 is connected as by welding to a drive head 44 that overlies the upper end of the evaporator, and the drive head is connected through suitable speed reduction gear mechanism 45 to a drive motor 46. As shown in FIG. 1, the head has a threaded connection at 8 to the output member 49 of the reduction gear mechanism and suitable thrust bearings (not shown) are provided in the gear mechanism 45, to axially support the upper end of the ice remover. The ice removing drive mechanism 73 is conveniently supported on a detachable head 51 which extends into the upper end of the vessel 5 to be radially centered therein, and radial bearing means 52 are conveniently provided between the head 51 and the output member 49 of the drive mechanism, to radially support the ice remover. A discharge opening 53 is provided in the vessel 25 adjacent its upper end to allow the flake ice to be discharged therefrom.

The ice remover is arranged so that the helical ice engaging surface generates a non-cylindrical or undulated surface of revolution as it rotates relative to the freezing wall. As best shown in FIG. 2, the freezing wall 11 is advantageously in the form of a circular cylinder to provide a smooth freezing surface to facilitate removal of ice therefrom and the helical ice engaging surface on the ice remover is formed with a noncircular configuration as viewed in a direction axially of the ice remover so that different portions of the helical ice engaging surface are spaced relatively different distances from the freezing wall. This noncircular configuration can be achieved, for example, by winding the helical coil on a noncircular mandrel, or alternatively, by laterally deforming a circular helical coil after it has been wound. In the embodiment illustrated in FIGS. 1-3, the helical ice engaging surface is made generally elliptical in form, as viewed in a direction axially of the coil, to provide a minor diameter in a plane through diametrically opposite points indicated at a and b and a major diameter in a plane through diametrically opposite points indicated c and d which are angularly offset approximately 90° from the plane of the points a and b. In this embodiment, the minor diameter is selected so as to be somewhat larger than the outer diameter of the freezing wall 11 by an amount corresponding to the minimum thickness of the flake ice desired. For example, if the minimum flake thickness desired is of the order of .01 to .03 inch, the minor diameter should exceed the outer diameter of the freezing wall by about twice the minimum desired flake thickness. The major diameter is made substantially larger than the minor diameter, and preferably at least double the difference between the minor diameter of the ice remover and the outer diameter of the freezing wall so as to provide an ice layer having a thickness which varies of the order of .00% or more.

As the noncircular helical ice removing surface rotates, the ice removing surface generates a non-cylindrical or undulated surface of revolution somewhat as shown in phantom in FIGS. 1 and 3 with the ridges of the envelope located at those axial points along the evaporator that register with the major diameter points such as c and d

on the ice remover while the valleys correspond to those axial locations on the evaporator which are aligned with the minor diameter points such as a and b on the ice remover. This envelope describes the thickness of the ice layer which can build up on the evaporator before it is engaged by the ice engaging surface of the ice remover and, as will be seen, the ice layer can build up to a non-uniform thickness of alternately thick and thin areas at longitudinally spaced locations along the evaporator. This arrangement provides relatively weaker areas in the ice layer, in the regions adjacent the valleys, and facilitates removing the ice from the evaporator in smaller sections. It is considered that removal of ice in smaller sections from the evaporator reduces the peak torque loads on the ice remover drive mechanism from that encountered when the entire ice layer is removed at one time and, moreover, reduces the axial stresses and elongation of the ice remover.

The helical ice engaging surface of the ice remover is preferably made blunt and noncutting so that it does not merely scrape off the surface of the ice layer but instead rides across the ice layer with a progressively increasing pressure as the ice layer thickens until the pressure applied by the ice engaging surface to the frozen layer in a direction parallel to the freezing surface is sufficient to overcome the bonding force of the ice to the freezing wall. Since the freezing wall is formed with a smooth cylindrical surface, it does not have any ridges or valleys which would impede free removal of ice therefrom or form pockets in which scale or lime from the water can collect. Preferably, the ice engaging surface is formed as shown with a convex cross section with a radius that is large as compared to the spacing between the ice engaging surface and the freezing wall. Since the noncircular helical ice engaging surface generates an undulated surface of revolution as it rotates, the ice layer will have a similarly undulated outer surface to thereby form ice flakes of varying thickness.

While the helical ice engaging surface is shown in FIGS. 1-3 as having an elliptical configuration, as viewed in a direction axially of the ice remover, the ice engaging surface can have other noncircular configurations, but the noncircular configurations are preferably symmetrical with respect to the axis of rotation of the auger.

The ice making apparatus as illustrated in the embodiment of FIGS. 4 and 5 is the same as that shown in FIGS. 1-3 except for the modified ice remover, and like numerals are used to designate the same parts described in connection with the first embodiment. As in the preceding embodiment, the freezing wall 11 is preferably of cylindrical configuration with a circular cross section. The rotary ice removing device 143 for removing ice from the freezing wall has a helical ice engaging surface 143a. The ice remover is preferably in the form of a helical member having one end supported against axial movement. As shown, the helical member has its upper end connected, as by welding to the drive head 144 that overlies the upper end of the evaporator for rotation by the drive means 45 relative to the evaporator.

The ice remover of this embodiment is also advantageously arranged so that the helical ice engaging surface generates a non-cylindrical or undulated surface of revolution as it rotates relative to the freezing wall. In order to facilitate radial balancing of the forces on the ice remover, the helical ice engaging surface is preferably formed with a generally triangular configuration as viewed in a direction axially of the ice remover. As best shown in FIG. 5, the generally triangular ice remover has three "inner" ice engaging portions designated e, f and g on its ice engaging surface which are angularly spaced apart, and three "outer" ice engaging portions m, n and o, intermediate the inner portions e, f and g. The inner portions e, f and g are arranged to extend relatively closer to the outer surface of the freezing wall 11 than the outer portions m, n and o and, since the aforescribed inner por-

tions *e*, *f* and *g* are spaced apart along the helical ice engaging surface, they extend closely adjacent the freezing wall in zones spaced apart in a direction paralleling the axis of the freezing wall.

In general, the ice layer can build up on the freezing wall until it is engaged by a portion of the rotary ice remover. When the ice remover is rotated, the inner and outer portions move in annular paths around the freezing wall and the inner portions limit ice layer build-up to a relatively thin layer in the annular zones transversed by the inner portions, while the outer portions allow the ice layer to build up to a relatively thicker layer before removal. The outer portions *m*, *n* and *o* are accordingly spaced radially from the freezing wall a distance corresponding to the desired maximum flake thickness and may, for example, be spaced of the order of .100" to $\frac{1}{8}$ " for relatively thick flakes. A smaller spacing could of course be used, if desired. The inner portions provide thin relatively weak areas in the ice layer at spaced points along the freezing wall which is considered to facilitate removal of the ice in smaller segments and thus reduce peak torque loads on the ice remover drive motor. The inner portions may also advantageously be used to radially center the ice remover relative to the freezing wall and for this purpose are shaped to extend closely adjacent and preferably into engagement with the freezing wall 11. Since the inner portions are angularly spaced around the evaporator, they provide an automatic centering action which maintains the outer portions of the ice remover radially spaced a uniform distance from the freezing wall. This provides better control over the flake thickness by inhibiting lateral movement of the ice remover relative to the freezing wall during ice removal.

The noncircular configuration of the ice remover 143 can conveniently be achieved by winding the helical member on a mandrel having the general configuration desired. The outer portions *m*, *n* and *o* of the ice remover are conveniently of arcuate configuration as viewed in an axial direction with a radius exceeding that of the freezing wall by the desired flake thickness so that the outer portions provide generally uniform flake thickness in the zones circumscribed thereby. In the form shown, the inner portions extend generally along lines tangent to the freezing wall. The outer periphery 143b of the helical member can be ground after forming to provide a generally circular outer periphery on the ice remover as shown in FIG. 5. As shown in FIG. 4, the helical member 143 has a relatively higher helix angle than that used in FIGS. 1-3 and this increases the axial spacing between zones traversed by the inner portions of the ice remover.

The ice making apparatus shown in the embodiment of FIGS. 6-9 is also the same as that described in connection with FIGS. 1-3 except for the ice remover, and like numerals are used to designate the same parts. As in the preceding embodiments, the freezing wall 11 is preferably of cylindrical configuration with a circular cross section. The rotary ice remover 243 is preferably in the form of a helical member secured to a drive member 244 and having helical ice engaging surface 243a. The ice remover has a plurality of protuberances, preferably three in number and designated 244a-244c, at points spaced along the ice engaging surface, which protuberances extend inwardly from the ice engaging surface 243a and define inner ice engaging portions. As will be seen from FIG. 7, the ice engaging surface 243a with the protuberances 244a-c thereon has a noncircular configuration as viewed in an axial direction. However, the protuberances are preferably provided only at certain locations on the ice engaging surface, as described hereinafter, and are arranged in the same position on each convolution. The protuberances are angularly spaced apart about the axis of the ice remover and the three protuberances are preferably employed and located at points angularly spaced apart about 120° from each other as viewed in an axial direction shown in FIG. 7. The protuberances are also

spaced along the helical ice engaging surface so that they are spaced apart in a direction parallel to the axis of the ice remover and, preferably, are located to engage the freezing wall at a point approximately midway of the length of the freezing wall and at points about half way between the mid-point and each end of the freezing wall, as shown in FIG. 6. One of the protuberances such as 244b can be readily located at approximately the mid-point of the freezing wall. However, the location of the other protuberances in a direction axially of the ice remover must be correlated with the aforescribed desideratum that the protuberances be angularly located at approximately 120° intervals. With the helical ice remover shown, the desired axial location of the other protuberances 244a and 244c is approximately achieved by locating these last protuberances about 240° from the protuberance 244b, measured in a direction along the helix. In other words, the several protuberances are preferably spaced apart along the helical member 120° or multiples of that angle, depending on the number of convolutions in the helical member, to the end that the protuberances engage the freezing all adjacent its mid-point and at two other locations intermediate the mid-point and each end of the ice remover. For very long freezing walls and ice removers, a greater number of protuberances may be used, if desired.

The ice engaging surface 243a is radially spaced from the freezing wall a distance corresponding to the desired flake thickness and may, for example, be spaced of the order of .100" to .125" for relatively thick flakes. A smaller spacing could of course be used, if desired. The protuberances preferably extend into engagement with the freezing wall to radially center the ice remover and maintain a uniform spacing of the ice engaging surface from the freezing wall. The protuberances are preferably formed of a material which minimizes friction and wear on the freezing wall and the latter is also preferably formed of a wear-resistant material. For example, the freezing wall can be formed of a metal such as "Monel" metal which is corrosion resistant and the protuberances can be formed of a different material. The protuberances can be formed of metal secured or deposited as by welding on the ice remover or may be formed of a suitable plastic such as "nylon" secured as shown in FIG. 9 by embedding in a recess or socket 245 in the ice remover. A means such as a set screw 246 is advantageously threaded into the socket to enable adjustment of the protuberances in a direction radially of the ice remover to accommodate wear and to enable radial centering of the ice remover.

As will be seen, the helical ice engaging surface 243a with the protuberances thereon defines a noncircular ice engaging surface which, when the ice remover is rotated, generates a non-cylindrical or undulated surface of revolution about the freezing wall. Since the protuberances are small and spaced far apart along the ice remover, the undulated surface generated by the ice remover has wide flat bands in the zones traversed by the surface 243a and relatively narrow valleys in the zones traversed by the protuberances. This provides weakened areas in the ice layer at spaced points therealong which are considered to facilitate ice removal. Moreover, the protuberances also produce a centering action on the ice remover.

While the principles of the invention have been described above in connection with specific apparatus, it is to be understood that this description is made only by way of example and not as a limitation to the scope of the invention.

I claim:

1. In an apparatus for producing flake ice including an evaporator having a cylindrical freezing wall and means for refrigerating the same sufficient to freeze water thereon, means for supplying water to be frozen to said freezing wall, a rotary ice remover supported for axial

tation relative to said cylindrical freezing wall and having a helical ice engaging surface, and means for rotatably driving said ice remover, characterized in that the cylindrical freezing wall has a circular configuration as skewed in axial direction and the helical ice engaging surface has a noncircular configuration as viewed in a direction axially of the ice remover whereby different portions of the helical ice engaging surface are spaced relatively different distances from the freezing wall and generate an undulated surface of revolution as the ice remover rotates relative to the freezing wall.

2. An apparatus for producing flake ice including an evaporator having an outer cylindrical freezing wall and means for refrigerating the same sufficient to freeze water thereon, means for supplying water to be frozen to said outer freezing wall, an annular ice remover supported for axial rotation relative to said cylindrical freezing wall and having an internal helical ice engaging surface spaced from said freezing wall and extending therearound, and means for rotatably driving said annular ice remover, characterized in that the cylindrical freezing wall has a circular configuration as viewed in an axial direction and the helical ice engaging surface has a noncircular configuration as viewed in a direction axially of the ice remover whereby different portions of the helical ice engaging surface are spaced relatively different distances from the freezing wall and generate an undulated surface of revolution as the ice remover rotates relative to the freezing wall.

3. An apparatus according to claim 2 in which the helical ice engaging surface has a generally elliptical configuration as viewed in a direction axially of the annular ice remover.

4. An apparatus according to claim 2 in which the major internal diameter of helical ice engaging surface exceeds the minor internal diameter by an amount at least equal to the difference between the minor internal diameter of the ice engaging surface and the outer diameter of the freezing wall.

5. An apparatus according to claim 2 in which the ice remover comprises an axially expandable and contractible helical coil.

6. An apparatus according to claim 2 in which the means for supplying liquid to the freezing wall includes a vessel spaced from the freezing wall for containing liquid to thereby immerse the freezing wall in the liquid.

7. An apparatus according to claim 2 in which the helical ice removing surface has a convex cross section.

8. An apparatus according to claim 2 wherein said ice engaging surface has a generally triangular configuration as viewed in a direction axially of the annular ice remover.

9. An apparatus according to claim 2 wherein said ice engaging surface has at least three portions located at points spaced apart along the helical ice engaging surface intermediate the ends thereof which portions extend into running engagement with the cylindrical freezing wall, said last mentioned portions being angularly spaced approximately uniformly about the axis of the ice remover to radially center the ice remover on the freezing wall.

10. An apparatus for producing flake ice including an evaporator having an outer cylindrical freezing wall and means for refrigerating the same sufficient to freeze water thereon, means for supplying water to be frozen to said outer freezing wall, an annular ice remover supported for axial rotation relative to said freezing wall and having an internal helical ice engaging surface extending around the freezing wall, and means for rotatably driving said annular ice remover, characterized in that the cylindrical freezing wall has a circular configuration as viewed in an axial direction and said helical ice engaging surface has portions thereof spaced radially from said freezing wall according to the desired flake thickness and other portions intermediate said first mentioned portions which extend relatively closer to said

cylindrical freezing wall at points spaced apart axially along the freezing wall whereby said ice engaging surface generates a non-cylindrical surface of revolution as the ice remover rotates relative to the freezing wall.

11. An apparatus according to claim 10 wherein said other portions of said ice engaging surface extend into engagement with said cylindrical freezing wall and are disposed at least at three different angular locations about the annular ice remover to radially center the ice remover on the freezing wall.

12. An apparatus according to claim 10 wherein said other portions of said ice engaging surface are arranged in substantial radial symmetry as viewed along the axis of the annular ice remover and are spaced apart in a direction parallel to the axis of the ice remover.

13. An apparatus according to claim 12 wherein said other portions of said ice engaging surface extend into engagement with said cylindrical freezing wall to radially center the ice remover on the freezing wall.

14. An apparatus for producing flake ice including an evaporator having an outer cylindrical freezing wall and means for refrigerating the same sufficient to freeze water thereon, means for supplying water to be frozen to said outer freezing wall, an annular ice remover extending around said freezing wall and having inner ice engaging surface portions spaced from said freezing wall a distance corresponding to the desired flake thickness, the improvement comprising means defining evaporator engaging protuberances on said annular ice remover intermediate the ends thereof, said evaporator engaging protuberances extending radially inwardly from said ice engaging surface portions and disposed at least at three different angular locations about the axis of the annular ice remover to radially center the ice remover on the freezing wall, said protuberances being spaced apart in a direction paralleling the axis of said annular ice remover to engage said freezing wall in zones spaced apart axially along the freezing wall.

15. An apparatus according to claim 14 including means for adjusting said protuberances in a direction radially of the ice remover.

16. An apparatus for producing flake ice including an evaporator having an outer cylindrical freezing wall and means for refrigerating the same sufficient to freeze water thereon, means for supplying water to be frozen to said outer freezing wall, a helical ice remover extending around the outer freezing wall and supported for axial rotation relative thereto, means for driving said ice remover, characterized in that the cylindrical freezing wall has a circular configuration as viewed in an axial direction and the inner surface of the helical ice remover has ice engaging portions at locations spaced along the helical ice remover which ice engaging portions extend closely adjacent the outer freezing wall and other ice engaging portions intermediate said first mentioned ice engaging portions which are spaced radially from the freezing wall a distance greater than the spacing of said first mentioned portions, said first mentioned ice engaging portions, during rotation of the helical ice remover, traversing circular paths intermediate the circular paths traversed by said other ice engaging portions whereby the inner surface of the helical ice remover generates a noncylindrical surface of revolution as the ice remover is rotated relative to the freezing wall.

17. An apparatus for producing flake ice including an evaporator having an outer cylindrical freezing wall and means for refrigerating the same sufficient to freeze water thereon, means for supplying water to be frozen to said outer freezing wall, a helical ice remover extending around the outer freezing wall and supported for axial rotation relative thereto, and means for driving said ice remover, the improvement wherein said helical ice engaging surface the major portion of which is spaced radially from said freezing wall a distance corresponding to the desired flake thickness and said helical ice re-

mover has at least three evaporator engaging protuberances extending radially inwardly from the ice engaging surface at spaced locations along the helical ice engaging surface, said protuberances being disposed at least at three different angular locations about the axis of the ice remover and being spaced apart in a direction paralleling the axis of the ice remover to engage said freezing wall in zones spaced apart along the freezing wall.

18. An apparatus according to claim 17 wherein said protuberances are located to engage the freezing wall at zones spaced approximately uniformly along the freezing wall.
